UNITED STATES PATENT OFFICE.

RAYMOND J. WENKER, OF MILWAUKEE, WISCONSIN.

DENTAL FORM.

1,045,920.

Specification of Letters Patent.

Patented Dec. 3, 1912.

Application filed March 25, 1912. Serial No. 686,046.

To all whom it may concern:

Be it known that I, RAYMOND J. WENKER, a citizen of the United States, residing at Milwaukee, county of Milwaukee, and State 5 of Wisconsin, have invented new and useful Improvements in Dental Forms, of which the following is a specification.

My invention relates to improvements in that class of dental forms which are adapted 10 to be used by instructors in dentistry for demonstration purposes, and it pertains more especially, among other things, first, to the construction of the teeth supporting members which represent the gums, teeth 15 and a portion of the upper and lower jaws of a person, in which forms the roots of the teeth are embedded, and second, to the peculiar construction of the teeth by which they are more securely retained in place in such 20 members.

My invention is further explained by reference to the accompanying drawings, in which—

Figure 1 is a side view of one of the forms 25 which represents a portion of the lower jaw, part broken away, and Fig. 2 is a vertical section of the form shown in Fig. 1.

Like parts are identified by the same reference numerals in both views. 30 1 represents the body of the form which is preferably made of hard, black, vulcanized rubber, or other similar material.

2 represents the gums and exterior surface 35 of the form which is preferably made of soft flesh colored rubber or similar material.

3 represents a set of artificial teeth, the exterior or protruding ends of which are of ordinary construction, while their inner ends are preferably provided with notches 40 4, 4, in which notches the inclosing rubber or other like material is adapted to engage, whereby the teeth are securely retained in place.

It will be understood that the object of 45 forming the interior portion of the form 1 of hard material, is to more securely hold the teeth, whereby the liability of their becoming loose when being operated upon, is avoided, while the exterior portion 2 of the 50 form is made of softer yielding material so as to more closely resemble the natural gums of a person, which material, when required, may be forced down around the sides of the

teeth or pressed to one side, as circumstances may require, when operating on the teeth. 55

While I have shown and described a form which represents the lower jaw, gums and teeth of a person, it will be understood that in practice, a similar form is used to represent the upper jaw, gums and teeth. While 60 I preferably use vulcanized rubber in said forms to support the teeth, any equivalent material may, if desired, be substituted therefor.

While I have shown a full unbroken set of 65 teeth in the drawings, it will be understood that some of the teeth may be omitted to better demonstrate methods of constructing bridge work in connection therewith, and my invention is also intended to cover forms 70 in which a partial set of artificial teeth only are used in connection with a partial jaw, and while the interior is described as being hard and the exterior soft, it will be understood that the degree of hardness of such 75 material may be changed, providing, however, that the exterior surface is always preferably somewhat softer than the interior.

Having thus described my invention, what 80 I claim as new, and desire to secure by Letters Patent, is—

1. In a device of the described class, a dental form resembling a portion of one of the jaws of a person, comprising a hard interior 85 portion and a relatively softer yielding exterior portion, in combination with artificial teeth.

2. A dental form resembling a portion of one of the jaws of a person, comprising a 90 relatively hard interior portion and a yielding exterior portion, in combination with artificial teeth provided at their inner ends with retaining grooves or recesses.

3. A dental form resembling a portion of 95 one of the jaws of a person, comprising a relatively hard interior portion formed of black vulcanized rubber, and a yielding exterior portion, in combination with artificial teeth.

4. A dental form resembling a portion of one of the jaws of a person, comprising a 100 relatively hard interior portion and a yielding exterior portion formed of soft flesh colored vulcanized rubber, in combination 105 with artificial teeth.

5. A dental form resembling a portion of one of the jaws of a person, comprising a relatively hard interior portion formed of black vulcanized rubber, and a yielding exterior portion formed of soft flesh colored vulcanized rubber, in combination with artificial teeth.

In testimony whereof I affix my signature in the presence of two witnesses.

RAYMOND J. WENKER.
